Patented Apr. 12, 1966

204,425

CONTAINER FOR A THERAPEUTIC APPLIANCE AND ACCESSORIES

Louis V. Aronson II, Far Hills, and Seymour Rappoport,
Rumson, N.J., and Beverly Bond, South Norwalk,
Conn., assignors to Ronson Corporation, Woodbridge,
N.J., a corporation of New Jersey

Filed Jan. 6, 1964, Ser. No. 78,076

Term of patent 14 years

(Cl. D58—13)

Fig. 2.

Fig. 4.

Fig. 3.

FIG. 1 is a front perspective view of a container for a therapeutic appliance and accessories showing our new design;

FIG. 2 is a rear elevational view;

FIG. 3 is a bottom plan view;

FIG. 4 is an end elevational view; and

FIG. 5 is an exploded perspective view thereof.

The characteristic feature of the design resides in the appearance of the internal compartments which includes a reversed curved shaped section.

We claim:

The ornamental design for a container for a therapeutic appliance and accessories, substantially as shown and described.
